GARMENT

William E. Paulsen, Burlingame, Calif.

Application November 15, 1939, Serial No. 304,614

3 Claims. (Cl. 2--139)

My invention relates to garments, and has among its objects and advantages the provision of an improved shirt of the detachable collar type.

Shirts of the detachable collar type are characterized by a neckband to which the collar is attached, with the front ends of the collar overlapping the overlapping ends of the neckband. The four overlapping elements are secured through the medium of the usual collar button. Such an arrangement of parts results in a bulky mass and it is frequently difficult to insert the collar button through at least one button hole in the neckband and the two button holes of the collar. The back collar button frequently interferes with proper adjustment of the tie, and the two-point connection between the collar and the neckband does not always hold the collar in properly assembled relation with the neckband.

Accordingly, an object of my invention is to provide a shirt and detachable collar wherein novel means are incorporated for effectively connecting the collar with the shirt throughout the entire length of the neckband and the collar.

Another object is to provide a shirt and detachable collar wherein a slide fastener is utilized for detachably connecting the collar with the neckband of the shirt, in which the slide element of the fastener is utilized as a mount for the collar button so that the latter will effectively restrain the slide element from accidental shifting, and in which the button is inserted through one button hole in one end of the collar only for effectively connecting the two ends of the neckband and the two ends of the collar in assembled relation.

In the accompanying drawing:

Figure 1 is a fragmentary front elevational view of the upper part of a shirt illustrating my invention;

Figure 2 is a rear view of the collar flattened out for the sake of clearness;

Figure 3 is a view similar to Figure 1 illustrating the manner in which the collar is detachably connected with the neckband of the shirt;

Figure 4 is an enlarged sectional view along the line 4--4 of Figure 1;

Figure 5 is an enlarged sectional view along the line 5--5 of Figure 1; and

Figure 6 is a perspective view of the slide element of the fastener illustrating the manner in which the button is anchored thereto, the button being illustrated in section.

In the embodiment selected to illustrate my invention, the shirt 10 includes a collar band 14 which is stitched to the shirt along the line 16, 55

and the neckband preferably comprises pieces 18 and 20 between the upper marginal edges of which is secured the tape or strap 22 of a conventional slide fastener 24. Tape 22 is stitched to the pieces 18 and 20 along the line 26, and the tape extends the full length of the neckband 14.

The second strap or tape 28 of the slide fastener 24 is secured between the inner wall 30 of the collar 32 and a cloth strip 34, as by stitching 36, with the strip 34 and the inner wall 30 sewed to the outer wall 38 of the collar by stitching 40. Fig. 2 illustrates the strip 34 as being coextensive in length with the neckband 14, as well as the collar 32, and the strip is so arranged as to overlie the slide fastener 24 to provide an enclosure therefor so that the necktie will slide freely when being shifted within the collar for tying purposes. Fig. 2 also illustrates the collar 32 when fully attached to the shirt 10, with the slide element located at one end of the neckband and the collar.

Slide element 42 is provided with a button 44, and the button aligns with a button hole 46 in the strip 34. The button is inserted through the button hole 46 and through a button hole 48 in the other end of the collar, which secures the ends of the neckband 14 as well as the collar 32. Fig. 6 illustrates the slide 42, which is conventional, as being provided with a loop 50 to which the button 44 is attached through the medium of a ring 52. It will thus be seen that the collar 32 is effectively connected with the neckband of the shirt and that the connection is such as to prevent any separation between the collar and the neckband. At the same time, the collar is provided with one button hole 48 and the button hole 46 merely accommodates projection of the button through the strip 34, which strip functions to provide a covering for the slide fastener 24 to permit easy adjustment of the tie, which tie is positioned between the strip 34 and the wall 38 of the collar. Strip 34 is provided with a concaved edge 54 which narrows the strip intermediate its ends. I have found that such configuration of the strip 34 causes the latter to draw down tightly against the slide fastener 24 and to maintain its position.

Fig. 3 illustrates the collar 32 partly disconnected from the neckband 14, and the collar may be completely detached from the neckband. Fig. 3 also illustrates the neckband 14 as being tapered slightly from the end 56 in the direction of its opposite end 58, and the collar 32 is similarly angled for connection with the tape 28 of the slide fastener. Thus the slide fastener 24 at the

end 58 of the neckband will lie beneath the button hole 48, but the other end of the slide fastener, when closed, will lie higher than at the end 58 so as to bring the slide element 42 into proper alignment with the button hole 48 when the ends of the collar are overlapped preparatory to being buttoned. The buttoned connection between the slide element 42 and the collar effectively anchors the slide element against accidental shifting so that the collar will remain effectively connected with the neckband.

My invention provides a shirt and detachable collar combination in which the slide fastener provides continuous connection between the collar and the neckband and in which one button hole 48 coacts with the button 44 in such manner as to effectively connect the ends of the neckband 14 as well as the overlapping ends of the collar. The collar 32 may easily be connected and disconnected with respect to the neckband 14, and the slide fastener constitutes an effective connecting medium which facilitates interchangeability of the detachable collars. My invention eliminates the necessity for separate collar buttons such as are employed in connection with detachable collars and the strip 34 protects the tie from engagement with the slide fastener so that the tie may be shifted easily inside the collar.

Having thus described certain embodiments of my invention in detail, it is, of course, understood that I do not desire to limit the scope thereof to the exact details set forth except insofar as those details may be defined in the appended claims.

I claim:

1. The combination of a shirt having a neckband, a detachable collar having a single button hole located at one end thereof, a slide fastener connection between the collar and the neckband for detachably connecting the collar with the neckband, and a button carried by the slide element of said slide fastener for insertion through

said button hole, said slide fastener being angled with respect to the neckband and the collar to bring said slide element directly underneath said button hole in the buttoned condition of the collar and the slide fastener to one side of the button hole at the end of the collar opposite the slide element thereof when positioned for insertion of said button through said button hole.

2. The combination of a shirt having a neckband, a detachable collar having a button hole at one end, a slide fastener connection between the collar and the neckband for detachably connecting the collar with the neckband, a button carried by the slide element of said slide fastener for insertion through said button hole, said slide fastener being so angularly related to the neckband and the collar as to bring the slide element thereof directly underneath said button hole in the buttoned condition of the collar, with the button hole located to one side of the slide fastener at the end opposite the slide element thereof, and a strip secured to the collar for covering the slide fastener, said strip having a button hole for reception of said button.

3. The combination of a shirt having a neckband, a detachable collar having a button hole at one end, said collar having an outer wall, a slide fastener connection between the collar and the neckband for detachably connecting the collar with the neckband, a button carried by the slide element of said slide fastener for insertion through said button hole, said slide fastener being angled to bring the slide element thereof directly underneath said button hole in the buttoned condition of the collar, with the button hole located to one side of the slide fastener at the end opposite the slide element thereof, and a strip secured to the collar for extending over the slide fastener between the latter and the outer wall of the collar, said strip having a button hole for reception of said button.

WILLIAM E. PAULSEN.
